UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,376, dated October 31, 1882.

Application filed August 11, 1882 Term of patent $3\frac{1}{2}$ years.

To all whom it may concern:

Be it known that I, WINTHROP L. JACOBS, of East Orange, in the State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The design consists of small gem-like circular and right-lined figures, of various shapes and forms, overlying and closely filling a plain ground, and connected in small symmetrical groups of threes and fours by short right-lined angular stems. This is represented in the central band, A, of the accompanying photograph, which photograph, as a whole, represents the

design adapted for the purposes of a stair-carpet by the addition of the bands B B and C C, as fully shown in said photograph.

I claim—

1. The design for carpets, consisting of the figures A, substantially as shown and described.

2. The design for carpets, consisting of the band A and the bands B B and C C, substantially as shown.

3. The design for carpets, consisting of the band B, substantially as shown.

4. The design for carpets, consisting of the band C, substantially as shown.

5. The design for carpets, consisting of the bands B and C, substantially as shown.

WINTHROP L. JACOBS.
